TUNING CONTROL MECHANISM

William M. Hurst, Douglaston, N. Y., assignor to
Hazelton Research, Inc., Chicago, Ill., a corporation of Illinois

Application April 3, 1947, Serial No. 739,207

2 Claims. (Cl. 74—10.41)

1

This invention is directed to control mechanisms. Although the invention is suited for various applications, it is particularly useful for controlling the variable element of an adjustably tuned circuit and hence will be described in that environment.

Control mechanisms of many types are presently employed in connection with adjustably tuned electrical circuits for the purpose of adjusting the circuit to resonate at any selected one of a plurality of predetermined frequencies within a given operating frequency range. These mechanisms are ordinarily associated with the rotor of an air-dielectric condenser or with the adjustable core of a variable inductance element. Push-button tuning devices represent one well-known type of control mechanism, which are employed for such purposes. Prior control mechanisms comprise more or less complicated mechanical or mechanical and electric arrangements which are rather expensive to manufacture. Also, these prior control mechanisms are often bulky and hence objectionable for some purposes such as for airborne or portable installations wherein size and weight considerations sometimes predominate. Also, accuracy of the frequency settings of some control mechanisms heretofore employed has not been particularly exact for frequencies in the ultra-high-frequency portion of the frequency spectrum. Consequently, efforts to reduce the size and complexities of such arrangements have usually resulted in the sacrificing of accuracy.

It is an object of the invention, therefore, to provide a new and improved tuning control mechanism which is not subject to one or more of the above-mentioned disadvantages and limitations of prior such mechanisms.

It is another object of the invention to provide a simple, compact, relatively inexpensive, yet reliable tuning control mechanism.

It is a further object of the invention to provide a small tuning control mechanism which requires the manipulation of but a single simple control member to effect quickly and accurately the desired settings of a controlled element.

It is an additional object of the invention to provide a new and improved tuning control mechanism which is adapted for use with a scale having uniformly spaced graduations thereon although the law of variation of an element controlled by the mechanism may not be linear.

In accordance with the invention, a tuning control mechanism comprises a first means including a plurality of radially disposed spaced stop portions and a shaft rotatably supported by the first means. The mechanism also includes a crank, connected to the shaft for rotation with respect to the first means and having a stop portion at the free end thereof for selectively regis-

2

tering with individual ones of the stop portions, for establishing predetermined angular relationships between the first means and the crank. A follower is pivotally connected to the crank for actuation thereby and has a first portion movable with reference to any selected one of the registering stop portions for positioning a controlled element in accordance with the relative positions of the first means, the crank, and the follower. 5 The follower has a second portion remote from the stop portion of the crank and the axis of the shaft. The control mechanism further includes a plurality of radially disposed adjusting screws on the first means for selective engagement with the second portion of the follower for adjusting the follower about the pivotal connection therefor with reference to any selected one of the registering stop portions, thereby to permit for each of the predetermined angular relationships between the 10 first means and the crank an adjustment of the position of the controlled element which is independent of the corresponding predetermined angular relationship between the first means and the crank. The control mechanism includes 15 means connected to the crank and the follower for biasing the second portion of the follower into engagement with individual ones of the adjusting screws and also includes a locking means on the first means for maintaining each of the 20 adjusting screws in a selected position of adjustment.

For a better understanding of the present invention, together with other and further objects thereof, reference is had to the following description taken in connection with the accompanying drawing, and its scope will be pointed out in the appended claims.

In the drawing, Fig. 1 is a rear elevational view of a tuning control mechanism in accordance 40 with the invention; Fig. 2 is a sectional view on the line 2—2 illustrating also the connection to a device controlled thereby; Fig. 3 is an elevational view of a portion of the arrangement of Fig. 1 showing a linkage connection secured thereto; Fig. 4 is a simplified representation of the arrangement of Fig. 1 illustrating two positions of adjustment thereof; and Fig. 5 represents the tuning curve of an electrical device which is associated with the control mechanism of Fig. 1.

50 Referring now to Fig. 1 of the drawing, the tuning control mechanism in accordance with the present invention comprises a first means or disc 10 constructed of a suitable material such as metal or plastic and including a plurality of radially disposed stop portions 11, 11 on the rear face thereof. These stop portions may be in the form of tapered notches which are preferably equally spaced near the periphery of the disc 10. The disc 10 also includes a pair of elongated apertures 20, 20 which are adapted to receive screws

for attaching the disc to a control panel or to the chassis of an electrical apparatus (not shown). The control mechanism also includes a second means in the form of a crank 12 of spring material such as steel, one end of which has a suitable bore therein which is attached by way of a press fit to a shaft 13 (see also Fig. 2). The shaft 13 is rotatably supported in a bore 14 in the disc 10 and carries at the end which projects beyond the front surface 15 of the disc a control knob 16 for rotating the shaft. The crank 12 is therefore rotatable relative to the disc 10 and is provided with a stop portion 18 at the free end thereof, preferably in the form of a rounded head on a pin 19 which passes through an aperture in the crank as illustrated in Fig. 2 of the drawing. Stop portion 18 is adapted selectively to co-operate with individual ones of the radially disposed stop portions 11, 11 on the disc 10, for establishing predetermined relative positions, specifically predetermined angular relationships between the disc 10 and the crank 12, as will be explained subsequently.

The control mechanism also includes a third means in the form of a follower 21 which is pivotally connected by the shank portion of the pin 19 to the crank 12 for actuation thereby. The follower 21 is a plate having the approximate shape of a parallelogram and is preferably disposed between the crank 12 and the flat surface 55 on a cylindrical shoulder 23 (see Fig. 2) which acts as bearing surface for the follower. The latter is provided with an elongated aperture 24 through which the shaft 13 extends in order to engage the crank 12. The follower 21 has a portion 26 which is remote from the pivot comprising the pin 19 and which is movable with respect to any selected one of the co-operating stop portions 11, 18 for positioning a controlled element, presently to be described, in accordance with the relative positions of the disc 10, the crank 12, and the follower 21.

The remote portion 26 of the follower 21 includes a pivot pin 29 which is connected to the movable element or rotor (not shown) of a condenser 30 which, in combination with a conventional winding (not shown), may comprise the tunable portion of an electrical circuit. The rotor of the condenser 30 is attached to a shaft 31 which is coaxial with the shaft 13 of the control mechanism. Shaft 31 is mechanically coupled to the pin 29 on the follower 21 through a crank 32 having a pin 33 at the free end thereof and a link 34 (see also Fig. 3). The latter has notches 35, 35 at the opposite ends thereof which receive the pins 29 and 33. The pins are maintained in their positions in the notches by means of a coil spring 37 having the looped ends thereof snapped over the pins.

The follower 21 also includes a second portion 40 (see Fig. 1) which is remote from the stop portion 18 of the crank 12 and the axis of the shaft 13. This portion is at one of the corners of the parallelogram and carries a hardened steel roller 41 which is rotatably mounted on the undersurface of the follower by a pin 42. The roller 41 projects into an annular recess 44 on the rear portion of the disc 10.

The control mechanism in accordance with the invention also comprises a plurality of adjusting screws 45, 45 which are radially disposed in the disc 10 adjacent the stop portions 11, 11. These screws extend from near the periphery of the disc 10 into the annular recess 44 for the purpose of adjusting the position of the movable

portion 18 of the follower 21 with respect to any selected one of the co-operating stop portions, thereby to permit for each of the predetermined angular relationships of the crank 12 with respect to the disc 10 an adjustment of the position of the rotor of the condenser 30 which is independent of the corresponding predetermined relative position for the disc and the crank. These screws preferably have hardened ends 46 to prevent cold working or deformation by the action of the roller 41 which is biased into engagement with individual ones of the pins by means of an arcuate spring 47 that is restrained with its ends lodged between a lug 48 on the crank 12 and the head of the pin 42. Locking screws 49, 49 are mounted in suitable bores near the front surface 15 of the disc 10 for engaging and maintaining each of the adjusting screws 45 in a selected position of adjustment.

Considering now the operation of the described control mechanism, rotation of the control knob 16 through an angle produces a corresponding angular movement of the shaft 13 and the crank 12 which is secured thereto. This angular movement of the crank 12 causes the stop portion 18 thereon comprising the rounded head of pin 19 alternately to snap into and to ride out of the successive stop portions 11, 11 on the disc 10 because of the resilient nature of the crank. The crank 12 drives the follower 21 in the same direction that it moves through the pivot pin 19. The roller 41 on the follower 21, which is biased in a direction away from the shaft 13 by the spring 47, is maintained by the spring in engagement with the ends 46, 46 of the successive screws 45, 45 so that the pin 29 on the remote portion 26 of the follower 21 moves in an arcuate path about the shaft 13. Neglecting for the moment the accurate adjusting feature provided by the screws 45, 45, the pin 29 acting through the link 34, the pin 33, the crank 32, and the shaft 31 turns the rotor of the condenser 30 by an amount corresponding effectively to the rotation imparted to the shaft 13 by the control knob 16, thereby adjusting the tunable circuit including the condenser 30 a given amount. The turning of the knob 16 is discontinued when the stop portion 18 engages the selected one of the radial stop portions 11. Rotation of the knob 16 so that the stop portion 18 rests in a different stop portion 11 rotates the shaft 31 and establishes the rotor of the condenser 30 in a new position of adjustment in the manner described above.

To effect an extremely accurate setting of the control mechanism at any of the co-operating stop portions and, hence, the corresponding setting of the condenser 30 which is controlled thereby, a locking screw 49 is loosened and the particular adjusting screw 45 is adjusted either in or out with respect to the periphery of the disc 10 depending on the sense of the required adjustment. The locking screw 49 is then tightened. When a screw 45 is adjusted outwardly, as shown for position A in Fig. 4, the roller 41 rests against the end 46 of the screw so that the follower 21 assumes the position shown in broken-line construction with the pin 29 disposed at position A'. When the screw 45 is adjusted inwardly with respect to the periphery of the disc 10 to the position B illustrated in Fig. 4, the follower 21 is displaced by the action of the adjusting screw 45 on the roller 41 so that the follower rests in the position shown in dash-dot line construction with the pin 29 at the position B'. It will be manifest from the illustration that the elongated aperture 24 in

the follower 21 permits the latter to oscillate as well as rotate about the shaft 13. It has been determined experimentally that the pin 29 may be adjusted by an amount which is a substantial portion of, and, in fact by an amount which is greater than the distance between successive stop portions 11, 11 with the crank 12 resting at any one of the predetermined positions therefor. While the adjustment has been described in connection with a single stop for the crank 12, it will be manifest that a similar adjustment may be made by manipulating the proper adjusting screw 45 at any other of the co-operating stops.

Curve C of Fig. 5 represents the frequency-angular displacement characteristic of an adjustably tuned electrical device which may be associated with the control mechanism of the instant invention. It will be observed that this curve varies considerably from linearity. In spite of this nonlinear tuning characteristic, the wide range of adjustment afforded at individual stop positions on the instant control mechanism permits the use of this mechanism with such an electrical device. Also, the uniform spacing between individual position stops presents no drawback in spite of the nonlinearity of such a tuning curve. The instant stop mechanism may, therefore, be employed in conjunction with a scale having uniformly spaced graduations thereon for indicating the position of the controlled element at each of a plurality of positions of adjustment thereof.

With the instant arrangement, the force required to operate the control knob 16 in a clockwise direction is substantially the same as that required to turn the knob in a counterclockwise direction, thus imparting a uniform "feel" to the control knob.

While a control mechanism has been described in connection with stop portions 11, 11 which are equally spaced, it will be clear that for some applications these stop portions may have an unequal spacing. It will also be manifest to one skilled in the art that the rotary motion imparted to a controlled element by the pin 29 may be converted to reciprocating motion by well-known mechanical arrangements if desired. It will also be clear that mechanisms other than tunable electrical devices may be controlled by the control mechanism of the present invention.

From the foregoing description, it will be manifest that a control mechanism in accordance with the present invention is compact, relatively inexpensive, reliable, and capable of a wide range of adjustment.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A tuning control mechanism comprising: a first means including a plurality of radially disposed spaced stop portions; a shaft rotatably supported by said first means; a crank, connected to said shaft for rotation with respect to said first means and having a stop portion at the free end thereof for selectively registering with individual ones of said stop portions, for establishing predetermined angular relationships between said first means and said crank; a follower pivotally

connected to said crank for actuation thereby and having a first portion movable with reference to any selected one of said registering stop portions for positioning a controlled element in accordance with the relative positions of said first means, said crank and said follower; said follower having a second portion remote from said stop portion of said crank and the axis of said shaft; a plurality of radially disposed adjusting screws on said first means for selective engagement with said second portion of said follower for adjusting said follower about the pivotal connection therefor with reference to any selected one of said registering stop portions, thereby to permit for each of said predetermined angular relationships between said first means and said crank an adjustment of the position of said controlled element which is independent of the corresponding predetermined angular relationship between said first means and said crank; means connected to said crank and said follower for biasing said second portion of said follower into engagement with individual ones of said adjusting screws; and locking means on said first means for maintaining each of said adjusting screws in a selected position of adjustment.

2. A tuning control mechanism comprising: a first means including a plurality of radially disposed spaced stop portions; a shaft rotatably supported by said first means; a crank, connected to said shaft for rotation with respect to said first means and having a stop portion at the free end thereof for selectively registering with individual ones of said stop portions, for establishing predetermined angular relationships between said first means and said crank; a follower pivotally connected to said crank for actuation thereby and having a first portion remote from said stop portion of said crank and movable with reference to any selected one of said registering stop portions for positioning a controlled element in accordance with the relative positions of said first means, said crank and said follower; said follower having a second portion remote from said stop portion of said crank and the axis of said shaft; a plurality of radially disposed adjusting screws adjacent said stop portions on said first means for selective engagement with said second portion for adjusting said follower about the pivotal connection therefor with reference to any selected one of said registering stop portions, thereby to permit for each of said predetermined angular relationships between said first means and said crank an adjustment of the position of said controlled element which is independent of the corresponding predetermined angular relationship between said first means and said crank; a spring connected to said crank and said follower for biasing said second portion of said follower into engagement with individual ones of said adjusting screws; and locking means on said first means for maintaining each of said adjusting screws in a selected position of adjustment.
